UNITED STATES PATENT OFFICE

JOHN M. HOPWOOD, OF PITTSBURGH, PENNSYLVANIA

FUEL-AIR RATIO CONTROL SYSTEM

Application filed May 7, 1930. Serial No. 450,404.

This invention relates to a fuel-air ratio control system for furnaces, and more particularly to a system wherein the admission of air into a furnace burning powdered coal is controlled in accordance with the variations in the carbon dioxide content of the products of combustion or gases escaping from said furnace.

This invention is particularly adapted to be used on furnaces in which the outlet damper and the feeding of fuel thereto are controlled by variations in the steam pressure. In such a control system when the steam pressure demands more fuel the regulator controlling the fuel feeder is opened and more fuel is admitted. As the same time the outlet damper on the furnace is automatically opened and the draft through the furnace is increased. The furnace draft damper is also automatically opened increasing the air supply.

This arrangement, however, cannot be depended on to maintain the proper fuel-air ratio as there is nothing in the system that is responsive to a change in heating value of the coal, or to its physical condition, that might affect the amount of coal which would be handled for a given speed of the feeder.

If the fuel-air ratio is incorrect for proper combustion, a change in the carbon dioxide content of the gases produced by the combustion takes place. This change in the carbon dioxide content of the gases causes the furnace to operate at a decreased efficiency, that is, the furnace operates under other than the most favorable conditions for which it was designed.

One object of this invention is to provide means for making a final adjustment of the fuel-air ratio in a furnace burning powdered coal in accordance with and by means of the carbon dioxide content of the escaping gases.

This and other objects which will be apparent to those skilled in this particular art

are obtained by means of this invention, one embodiment of which is set forth in the following specification and illustrated in the accompanying drawings forming a part hereof and in which:

Figure 1 is a schematic illustration of a boiler furnace and a control system therefor embodying the invention;

Fig. 2 is a view in front elevation of an auxiliary regulator for modifying the air delivered to the furnace in accordance with variations in the carbon dioxide content of the products of combustion.

Fig. 3 is a view in side elevation of the regulator shown in Figure 2.

Fig. 4 is an enlarged fragmentary view, partially in section, of the device illustrated in Figs. 2 and 3;

Fig. 5 is a top plan view of a portion of the device illustrated in Fig. 4; and

Fig. 6 is a diagrammatic illustration of circuits and apparatus embodied in the system shown in Fig. 1.

Similar reference characters refer to similar parts throughout the several views.

In the drawings a master regulator or relay 1 is shown of the type described in Letters Patent No. 1,787,407, granted December 30, 1930 to Thomas A. Peebles, and in application, Serial No. 361,657, filed May 9, 1929 by Thomas A. Peebles for combustion control system.

This regulator is suitably connected by a pipe 2 with the steam header 3 of the furnace. When variations in the steam pressure occur, the regulator 1 sends out impulses to the receiving regulators 4 and 5 of the type described in said Letters Patent No. 1,787,407, and which regulate the fuel and air admitted to the furnace. If the plant load has been increased, for example, there will be a decrease of pressure in the steam header on account of an increased resistance to the flow of steam through the super heaters, non-return valves, etc. In response to

this decrease in steam pressure, the master regulator 1 will operate and modify the pressure impulses transmitted to said receiving regulators to rebuild the steam pressure.

5 The regulator 4 controlling a rheostat 6 on a feeding motor 6', operates to increase the speed of said motor, whereby more powdered coal is fed to the furnace. At the same time the receiving regulator 5 opens the 10 damper 7 in the stack. The opening of the damper in the stack increases the suction in a furnace and the controller 16, such as shown in Letters Patent No. 1,800,400, granted April 14, 1931 to Thomas A. Peebles which 15 is balanced to maintain a furnace combustion chamber pressure is put out of balance. To maintain the predetermined furnace chamber pressure the controller 16 operates to open the air control damper 15 thereby 20 increasing the air delivered to the furnace until the furnace chamber pressure has been brought back to standard. On an increase in steam pressure the reverse operation takes place, the fuel and air supply to the furnace 25 being decreased.

The powdered coal feeder 10 for the furnace is supplied with air from the forced draft fan 11 through a pipe 12. A secondary air pipe 13 leads from the fan 11 to a burner 30 14 via duct 13' from which air is admitted to the furnace and in which the damper 15 is disposed.

In order to maintain a constant air pressure in the duct 13', and to insure a steady 35 supply of air for the furnace, a balanced controller 8, such as illustrated in said Patent No. 1,800,400 is provided. When the pressure of the air in the duct 13' varies beyond predetermined limits the controller 40 becomes unbalanced. To regain its equilibrium, the controller through its associated mechanism either opens or closes the damper 9, depending on whether the pressure is below 45 or above the determined minimum or maximum, increasing or decreasing the secondary air going into the duct until the pressure between the two dampers has been brought back to the predetermined standard. This regulator 8 may be attached as described or 50 it may be used to control the speed of the forced draft fan 11 directly and thus to maintain the pressure in said duct by varying the speed of the fan.

This arrangement is for the purpose of 55 maintaining a constant steam pressure in the boiler and while it makes a primary adjustment in the fuel-air ratio as described it cannot be depended on to maintain a proper fuel-air ratio. When the fuel-air ratio is correct the carbon dioxide content 60 of the gases produced by combustion is practically constant. When the ratio is incorrect the combustion of the powdered coal in the furnace is inefficient and variations occur 65 in the carbon dioxide content of said gases.

Therefore, to make a proper adjustment and to maintain the proper fuel-air ratio in the furnace a carbon dioxide recorder 17 of known type is provided which analyzes, and registers the carbon dioxide content of the 70 gases escaping from the furnace.

If the carbon dioxide content of the gases of combustion is too high, that indicates that the furnace is not receiving sufficient air, therefore, regulator 16 should open damper 75 15 wider than is necessary to maintain the furnace chamber pressure at that value which would otherwise be maintained therein by the regulator. When the carbon dioxide content is too low, that indicates that the furnace is 80 receiving too much air, hence regulator 15 should close the damper more or less until the proper fuel air ratio is attained.

The carbon dioxide recorder 17, a circuit controlling device 17' (see Fig. 6) operated thereby, auxiliary regulator 19 and a bellows 40 are arranged to so modify the operation of regulator 16, that, as the carbon dioxide content of the gases of combustion varies, either too high or too low, more or less air is 85 admitted to the furnace until the carbon dioxide content is of the proper value.

Regulator 16 comprises a fluid motor *a* and a pressure responsive device *b* for controlling the operation of the motor. 95

Motor *a* comprises a cylinder *c* having a reciprocating piston therein and a piston rod *d* to which is attached a frame *e*. The frame is connected to damper 15, so that as the frame moves up or down with the piston rod, damper 15 will be either closed or opened. A reversing valve *V* is mounted on the cylinder and controls the admission of pressure thereto. Thus, when the valve is moved to one position, the piston moves upwardly, and when moved to another the piston moves downwardly. 105

Valve *V* is controlled by device *b*. Thus when the pressure in the furnace chamber rises, the valve is shifted to effect upward movement of the regulator; or if the furnace chamber pressure falls, the valve is reversed to cause the frame to move downwardly.

Pressure responsive device *b* comprises a beam *f* fulcrumed at *h*, having inverted bells *i* and *j* attached to the opposite ends thereof. The bells are partially immersed in a liquid held in a tank *k*. The interior of bell *i* is subjected to atmospheric pressure by means of an open ended pipe *l* that extends upwardly through the bottom of the tank and into the interior of the float. 115

The interior of bell *j* is subjected to the furnace chamber pressure which is communicated thereto by a pipe 46. 125

Beam *f* is operatively connected to valve *V* by suitable linkage, indicated generally at *m*; the arrangement of the linkage is fully described in a copending application for Letters Patent, Serial No. 520,949, filed March 130

7, 1931, by George W. Smith, which is assigned to John M. Hopwood. The linkage is such that, as the bell *j* rises, in response to an increase in furnace chamber pressure, valve *V* is shifted by beam *f* and the linkage to that position in which upward movement of the regulator frame is affected, or if the bell falls, in response to a decrease in furnace chamber pressure, the valve is reversed to effect a downward movement of the regulator frame.

In order to cause regulator 16 to operate damper 15 in accordance with the carbon dioxide content of the regulator, a bellows 40 is provided. Bellows 40 operates upon an extension 40' of beam *f* upon which a weight *w* is disposed.

If the carbon-dioxide content of the gases of combustion is too low, recorder 17 and the circuit controlling device 17' therof causes auxiliary regulator 19 to transmit a pressure to the bellows 40, thereby causing it to expand. As it expands the beam is rocked counter clockwise, (that is in the same direction as an increase in pressure within bell *j* would rock it) thereby causing the regulator to shift damper 15 towards its closed position to reduce the amount of air delivered to the furnace.

When the carbon dioxide content is too high, auxiliary regulator operates to reduce the pressure in bellows 40, so that weight *w* becomes effective to rock beam *f* clockwise (that is, in the same direction as it would be rocked by bell *j* if the furnace chamber pressure were reduced), thereby to reverse valve *V* and cause the regulator frame to move downwardly to open damper 15 to increase the amount of air delivered to the furnace.

Auxiliary regulator 19 comprises a sending relay 19' which is operated by a solenoid-operated cam device N. Sending relay 19' is illustrated and fully described in Letters Patent No. 1,787,407, previously referred to herein.

Solenoid operated cam device N comprises a friction wheel 25 mounted on and secured to the shaft S and a cam 26 mounted on and secured to the shaft in spaced relation to the friction wheel. The particular form of cam illustrated is that of a circular disc mounted eccentrically on the shaft. Since the cam and wheel are secured to the shaft, the cam may be turned in one direction or the other by turning the friction wheel.

In order to provide for turning the friction wheel and the cam in a clockwise direction, a pawl or dog 22' is provided. Pawl or dog 22' is pivotally mounted between the outer end of two arms 25', the inner ends of which are loosely mounted on shaft S. Pawl 22' is provided with a gripping member 22" which is arranged to grip the friction wheel when the pawl is turned clockwise. Pawl 22' is operated by a solenoid 20 which is pro-

vided with a movable armature connected by a link 22 to the pawl. Thus, when solenoid 20 is energized, the armature will be attracted thereby and move link 22 upwardly.

As link 22 moves upwardly, the pawl is actuated into gripping relation with the friction wheel. The gripping action between the pawl and the friction wheel takes place during the initial upward movement of link 22. As the link continues to move upwardly, arms 25' will move upwardly with the pawl as friction wheel 25 turns. When solenoid 20 is deenergized, arms 25' are released thereby breaking the gripping relation between the pawl and the friction wheel. If the solenoid is again energized, the friction wheel will be turned or advanced a predetermined distance in a clockwise direction. Thus it will be apparent that by alternately energizing and deenergizing solenoid 20, friction wheel 25 and cam 26' may be advanced step-by-step in a clockwise direction.

When solenoid 20 is deenergized, arms 25' rest on an adjustment screw 31, and the outer end of pawl or dog 22' rests on a support 24. By adjusting set screws 31, the travel of cam 26 each time one or the other of the solenoids is energized may be increased or decreased as desired.

Counter-clockwise turning of cam 26' and friction wheel 25 may be attained by means of mechanism, such as that described above for effecting clockwise turning of the cam, disposed to operate on the opposite side of friction wheel 25. For simplicity, the elements of the counter-clockwise turning mechanism are designated by the same reference characters.

Counter-clockwise turning of cam 26' by means of the mechanism above described is governed by a solenoid 21. Thus by alternately energizing and deenergizing solenoid 21, cam 26' and friction wheel 25 may be advanced in a counter-clockwise direction step-by-step.

Movements of cam 26' are utilized to operate sending relay 19'. The sending relay includes a floating lever 26, a multi-way valve 34, a pressure responsive bellows 35 that operates against a spring 36, and a push rod 37 which is mounted on the bellows. The upper end of push rod 37 is pivotally connected to floating lever 26.

One end of floating lever 26 is pivotally connected at 32 to linkage 33 that operates valve 34. The opposite end of floating lever 26 has a pin 27 attached thereto which rests on cam 26'. Pin 27 is yieldingly held in engagement with the surface of the cam by means of a spring 28, one end of which is attached to lever 26 and the other end of which is anchored at 29 to the housing 30 of sending relay 19'.

Valve 34 has an inlet port which is connected to a pipe line 47 having therein a

medium under pressure, such as air. The valve also is provided with an outlet port 48 that is connected to the interior of bellows 35 and to the interior of pipe 38 leading to indicator 39, and to the interior of a pipe line 49 that leads to the interior of bellows 40. Valve 34 also has an exhaust port 50.

When valve linkage 33 is moved downwardly, communication is established through valve 34 with pressure supply pipe 47 and the interior of bellows 35, pipe 38 and pipe line 49. Thus a pressure impulse is transmitted to bellows 40, which as stated hereinbefore, causes damper 15 to move towards its closed position. When pressure is applied to the interior of bellows 35 it expands and moves push rod 37 upwardly, thereby causing floating lever 26 to pivot about pin 27. Thus, valve linkage 33 is moved upwardly thereby closing off communication between the pressure line 47, the interior of bellows 35, pipe 38 and pipe line 49.

If valve linkage 33 is moved upwardly and above its neutral position, communication will be established between the interior of bellows 35, pipe 38 and pipe line 49 and the atmosphere through exhaust port 50. Thus the pressure within the bellows, pipe 38 and pipe line 49 will be reduced. When the pressure is reduced, bellows 35 contracts, thereby moving valve linkage 33 downwardly and returning the valve to its neutral position.

As stated previously herein a reduction in pressure in bellows 40, which occurs when the pressure in pipe line 49 is reduced, causes regulator 16 to open damper 15 to admit more air to the furnace.

When cam 26' is turning clockwise, valve 34 is operated to reduce the pressure in pipe line 39 and bellows 40 in the manner aforesaid. As stated previously herein the pressure in bellows 40 should be reduced when the carbon dioxide content of the gases of combustion is too high.

Counter-clockwise turning of cam 26' causes valve 34 to operate to increase the pressure in pipe line 49 and bellows 40 thereby to effect a closing of damper 15 and a reduction in the amount of air delivered to the furnace, when the carbon dioxide content is too low.

From the above it will be seen that solenoid 20 of auxiliary regulator 19 functions when the carbon dioxide content, of the gases of combustion, is too high, and that solenoid 21 operates to effect a closing of damper 15 and a reduction in the amount of air delivered to the furnace when the carbon dioxide content is too low.

In Fig. 6 of the drawings, the circuit connections between circuit controlling device 17', which is operated by the carbon dioxide analyzer 17, and solenoids 20 and 21, are schematically illustrated. The current for energizing the solenoids is derived from power

lines L1 and L2, a switch 51 being provided to either connect or disconnect the solenoids and the circuit controlling device 17' to or from the power lines.

Circuit controlling device 17' has a movable contact member 52 which when the carbon dioxide content of the gases of combustion are too high, engages a stationary contact member 53 whereby solenoid 20 is connected across power lines L1 and L2. Circuit control device 17', as stated previously herein, is of the type in which the movable contact member 52 is depressed at frequent intervals by a movable depressor bar (not shown) into engagement with contact member 53. Thus the circuit to solenoid 20 is alternately energized and deenergized to effect the step-by-step movement of cam 26' in a clockwise direction.

When the carbon dioxide content of the gases of combustion is too high, movable contact member 52 engages a stationary contact member 54, and when in the region of contact member 54 the depressor bar actuates contact member 52 into engagement with contact member 54, at predetermined intervals, whereby solenoid 21 is alternately energized and deenergized to effect step-by-step movement of cam 26' in a counter-clockwise direction.

If it is desired to manually control the energization of solenoids 20 and 21 push button switches 44 and 45 may be employed.

To manually increase the amount of air supplied to the furnace, when the carbon dioxide content is too high, push button switch 45 may be manually closed to thereby energize solenoid 20. Thus by alternately opening and closing switch 45 the step-by-step turning of cam 26 in a clockwise direction may be effected.

If it is desired to decrease the amount of air delivered to the furnace in case the carbon dioxide content of the gases of combustion are too low, push button switch 44 is alternately closed and opened to thereby alternately energize and deenergize solenoid 21, whereby the step-by-step turning of cam 26' in a counterclockwise direction is effected.

When the system is operating on automatic control, the switch operated by push buttons 42 and 43 is closed whereby movable contact member 52 of circuit controlling device 17' is connected to power line L2. Even though the switch operated by push buttons 42 and 43 is closed, the manual control of solenoids 20 and 21 may be utilized by operating push button switches 44 and 45 in the manner aforesaid.

If it is desired to operate solenoids 20 and 21 entirely on manual control, push button 43 is depressed to thereby disconnect movable contact member 52 from power line L2. Therefore, to manually control the carbon dioxide content of the gases of combustion,

switches 44 and 45 must be operated in accordance with the carbon dioxide content of the gases, as measured by analyzer 17.

For any given weight of gas passing through the boiler there will be a certain resistance to the flow from the furnace to the outlet of the boiler. This resistance is termed "the draft loss across the boiler" and must in each case be equal to the difference between the furnace draft and the outlet under the boiler damper. Therefore, when the furnace draft is changed, as is the case in controlling from carbon dioxide content as described, and the outlet damper remains constant, it follows that there must be a change in the weight of the gases passing through the boiler.

If the carbon dioxide of the gases escaping from the furnace goes above the value for which the recorder has been set, it will energize one of the solenoids which sends the impulse as described to the bellows 40 increasing the pressure therein. For the controller to remain in equilibrium the furnace suction must be decreased which is accomplished by the opening of the damper 15 increasing the amount of air passing into the furnace. Since the suction in the furnace has been decreased and the outlet draft remains constant the draft loss across the boiler has increased, increasing the amount of air passing into the boiler and making the proper fuel-air ratio correction by adjustment of said damper 15.

On the other hand if the carbon dioxide content becomes too low the reverse action of the carbon dioxide sender acts to increase the draft in the combustion chamber and to decrease the pressure in the bellows 40. To maintain the equilibrium of the controller the furnace suction must be increased. This can only be done by reducing the secondary air admitted to the furnace and the damper 15 is so adjusted. In this way the carbon dioxide content of the gases is again brought back to the correct value.

The carbon dioxide recorder is adjusted so that an analysis of the carbon dioxide content is made about every two minutes or slightly less. If one analysis proves to be either too high or too low an impulse is sent out from the sender and a definite pressure change in the bellows 40 results. This effects a slight adjustment in the fuel-air ratio but no continuing adjustment is made until there is another analysis made by the recorder. If this analysis shows the fuel-air ratio to be still incorrect another adjustment is made and so on until the correct fuel-air ratio is secured; otherwise no further adjustment occurs.

To speed up the adjustment in the fuel-air ratio, when the recorder shows the carbon dioxide content to be incorrect, one of the solenoids may be energized by actuating one

or the other of the push buttons 44 or 45 on the panel. This permits the CO₂ content of the gases to be regulated to the proper value without waiting for the automatic sending device to operate.

While I have described the preferred embodiment of my invention, it is obvious that certain additions, substitutions, variations or omissions may be made without departing from the spirit of my invention or the scope of the appended claims. For example, wherever I refer to a recorder registering the variations in CO₂ content I do not limit myself to a device which makes an actual record of the analyses although it is clear that I may use such a device. The recorder may, however, be merely a suitable indicating device either visual or sounding and operating in any suitable or preferred manner. In addition, while I may utilize the CO₂ content as the controlling factor, it is clear that I may in similar fashion utilize some other constituent of the gas, such as oxygen, nitrogen, or the like.

What I claim as new and desire to secure by Letters Patent is:

1. The combination in a fuel-air control system for a boiler furnace of means responsive to variations in steam pressure for regulating the supply of fuel to said furnace, means responsive to said steam pressure for controlling the outlet damper of said furnace, means responsive to the furnace chamber pressure for regulating the inlet damper and means for making a further adjustment in the inlet damper in accordance with the CO₂ content of gases escaping from the furnace.

2. The combination in a fuel-air control system for a boiler furnace of a regulator responsive to variations in steam pressure and adapted to transmit impulses therefrom in accordance with said variations, a plurality of regulators actuated by said impulses for controlling the admission of fuel to said furnace and operating the outlet damper of said furnace, a controller for maintaining a constant air pressure in a duct leading to said furnace, a recorder for registering CO₂ content in gases escaping from the furnace, a sending device energized by the variations in CO₂ registered by said recorder, having mechanism associated therewith for admitting air from said duct into the furnace.

3. The combination in a fuel-air control system for a boiler furnace of a regulator responsive to variations in steam pressure and adapted to transmit impulses therefrom in accordance with said variations, a plurality of regulators actuated by said impulses for controlling the admission of fuel to said furnace and operating the outlet damper of said furnace, a controller for maintaining a constant air pressure in a duct leading to said furnace and means for admitting air from

said duct into the furnace to maintain the proper fuel-air ratio in said furnace, said means comprising a recorder registering the variations in the carbon dioxide content of the gases escaping from said furnace, a plurality of solenoids having means whereby one of said solenoids is energized when the carbon dioxide content of said gases varies beyond predetermined limits and an eccentric cam actuated by said energized solenoid having mechanism associated therewith for controlling the admission of air to said furnace.

4. A device for admitting air into a boiler furnace in accordance with the carbon dioxide content of gases escaping therefrom comprising a recorder registering the content of carbon dioxide in said gases, a plurality of solenoids, means associated therewith to energize one of said solenoids when the carbon dioxide content varies beyond predetermined limits, an eccentric cam controlled by said solenoids and having connected therewith mechanism controlling the rate of delivery of air to said furnace.

25 5. A device for controlling the air supply in a boiler furnace in accordance with the CO₂ content in the gases escaping from said furnace, comprising a recorder for registering the CO₂ content of said gases, means connected into said recorder for making an electric circuit, when said CO₂ content varies from predetermined limits, a plurality of solenoids connected with the circuit controlling means, one of which is adapted to be energized when an electric circuit is made, an eccentric cam operated by said energized solenoid through an articulated linkage, a lever actuated by said cam, in turn actuating a pilot valve adapted to build up pressure in a bellows connected therewith, and means for transmitting the pressure to mechanism for controlling a damper regulating the furnace draft.

6. The combination in a fuel-air control system for a boiler furnace of means responsive to variations in steam pressure for regulating the supply of fuel to said furnace, means responsive to said steam pressure for controlling the outlet damper to said furnace, means responsive to furnace chamber pressure to control the inlet damper, and means for making a further adjustment in the inlet damper in accordance with the content of a selected constituent of the gases escaping from the furnace.

7. In combination, a valve mechanism having pressure increase, decrease and neutral positions, adapted to transmit variable pressure impulses to an actuating device, a cam for operating said valve mechanism, means including a solenoid for operating said cam in one direction thereby to actuate said valve mechanism to effect the transmission of increasing impulses to said actuating device, means including a solenoid for actuating said

cam in the opposite direction thereby to actuate said valve mechanism to effect the transmission of decreasing pressure impulses to said actuating device, means responsive to the pressure impulses delivered to said actuating device for returning the valve mechanism to neutral position after each operation of said valve mechanism, and means to selectively energize said solenoids.

In testimony whereof, I have hereunto subscribed my name this 6th day of May, 1930.

JOHN M. HOPWOOD.
